DESIGN FOR A COLLAPSIBLE, FOCUSING FIELD GLASS

Richard Morbee, Chicago, Ill.

Application February 25, 1946, Serial No. 126,890

Term of patent 7 years

(Cl. D57—1)

To all whom it may concern:

Be it known that I, Richard Morbee, a citizen of the United States, residing at Chicago, in the county of Cook and State of Illinois, have invented a new, original, and ornamental Design for a Collapsible, Focusing Field Glass, of which the following is a specification, reference being had to the accompanying drawing, forming part thereof.

In the drawing:

Figure 1 is a plan view of a collapsible, focusing field glass, showing the binoculars adjusted in retracted position and out of focus, in carrying position;

Fig. 2 is a plan view of the device of Fig. 1, with the means for focusing the binoculars extended in open position and ready for sighting through;

Fig. 3 is an end view showing either top or bottom section of the field glass and the means for mounting the lenses of the binoculars; and

Fig. 4 is a side elevational view showing the folding devices used in focusing the binoculars and how they are affixed to the top and bottom sections of the field glass.

I claim:

The ornamental design for a collapsible, focusing field glass, as shown and described.

RICHARD MORBEE.
